UNITED STATES PATENT OFFICE.

SAMUEL M. KINTNER, OF PITTSBURGH, PENNSYLVANIA, AND JOHN W. LEE, OF BRANT ROCK, MASSACHUSETTS, ASSIGNORS, BY MESNE ASSIGNMENTS, TO SAMUEL M. KINTNER, OF PITTSBURGH, PENNSYLVANIA, AND HALSEY M. BARRETT, OF BLOOMFIELD, NEW JERSEY, RECEIVERS.

WIRELESS-TELEGRAPH RECEIVING APPARATUS.

1,132,588.

Specification of Letters Patent. Patented Mar. 23, 1915.

Application filed June 24, 1912. Serial No. 705,484.

To all whom it may concern:

Be it known that we, SAMUEL M. KINTNER and JOHN W. LEE, citizens of the United States, residing, respectively, at Pittsburgh, Pennsylvania, and at Brant Rock, Massachusetts, have invented certain new and useful Improvements in Wireless-Telegraph Receiving Apparatus, of which the following is a specification.

10 Our invention relates more particularly to receivers for wireless telegraphy of the type known as Fessenden's heterodyne receiver;—that is, a receiving system in which the signal is produced by combining with 15 the energy of the received electromagnetic waves, certain similarly timed locally produced impulses, which co-act with the received impulses; the indication being produced by the conjoint action of the two 20 sources of energy. In such receivers the tuning is of course very close and interference very little and consequently it is not so easy to find by trial, an incoming wave length not known beforehand.

25 The primary object of our invention is to combine with the heterodyne receiver, a ready and easily operated finding receiver.

We have illustrated the apparatus in one form in the accompanying drawing, where- 30 in—Figure 1 is a diagram showing a receiving apparatus embodying our invention and Fig. 1^a is a detail view of a convenient ar- 35 arrangement of mechanically connected tuning coils, preferably used therein. Fig. 2 is a modification of the invention using separate transformers for a receiver and a local generating circuit. Fig. 3 is a detail sketch of the coupled tuning condensers, 40 preferably used.

45 In Fig. 1 of the drawing, we represent a receiving antenna circuit from capacity 4 to ground at 5, which includes a variable con- 50 denser 6 shunted by the electrostatic tele- phone receiver 7; below this another con- denser 8, shunted by a switch 9 by which it may be cut out, the primary 10 of a trans- former, and a variable tuning inductance 11. The secondary 12 of the transformer is connected as by switch 13 to a local generating 55 circuit, or alternately by throwing the switch 13, to a local receiving circuit, comprising a condenser 14, detector 15, indicating tele- 60 phone 16 and potentiometer 17. The local 65 generating circuit connected to the second- 70 ary 12 comprises a tuning inductance 18, 75 one or more capacities 19, an arc 20, a vari- able impedance 21, and a local current 80 source 22.

As explained more fully in various patents of Fessenden, the heterodyne receiver oper- 85 ates briefly in this wise: The received wave currents flowing in the primary 10, are pe- 90 riodically augmented in their effects on the receiver 7 by locally produced oscillations generated in the secondary 12, by reason of 95 the oscillations produced in the circuit 18, 19, 20, through discharge of the current from 22, through the arc 20. Preferably the 100 periodicity of the circuit 12, 18, 19, 20, is very close to but not the same as the perio- 105 dicity of the antenna and the circuit 6, 7, and this produces beats which have an aug- 110 mented effect upon the receiver 7. The oper- 115 ation of this heterodyne receiver requires 120 that the relative periodicities of the antenna, 125 and the oscillating circuit excited by the 130 local source, shall be maintained in very 135 exact condition and all the said circuits very 140 closely tuned. It will be understood that 145 this device practically cuts out the effect of 150 all waves except those having a periodicity 155 with exactly the proper relation to the 160 periodicity of the oscillations in coil 12, pro- 165 duced by the local source. Therefore it is 170 not easy to "find" a signal of a different 175 periodicity not known to the operator. We 180 prefer to arrange the tuning coils 11 and 18, 185 respectively, in the antenna and the local 190 circuits in some mechanical connection, such 195 as illustrated at Fig. 1^a, such that the tuning 200 sliders upon the two coils move simultane- 205 ously and with the same or a proportional 210 effect. That is to say in changing the tune 215 of one circuit we change in like manner the 220 tune of the other circuit. By throwing the 225 switch 13 to the contacts 13^a, the heterodyne 230 generating circuit is cut out and the ordi- 235 nary detector circuit 14, 15, 16, 17, is cut 240 in, and this is preferably arranged with 245 what is called a broad tune, so that it can 250 pick up various waves. The operator listen- 255 ing on the telephone 16 tunes the antenna by 260 shifting the inductance 11 until he gets in 265 tune with received waves, and in doing so 270 has simultaneously shifted the tune of the 275 circuit 12, 18, 19, 20, so that the operator 280

can then re-throw the switch and receive without interference on the heterodyne receiver 7. In the frequent case when the variable capacities 6 and 19, are also used 5 for tuning, we preferably mount these two capacities, with a mechanical connection, such for example as shown in Fig. 3, by which they are likewise varied in unison. By this arrangement the operator may 10 rapidly run over various ranges of wave length within the limits of the heterodyne set and pick up any desired station and thereupon by the mere movement of the switch 13 receive without interference upon 15 the heterodyne receiver, or he may make further adjustments to secure maximum selectivity.

In Fig. 2, we have arranged to secure a better coupling for use of the ordinary 20 detector circuit. That is, we use a separate secondary 23 to connect the local receiving circuit 14, 15, 24, 16, 17. Otherwise the operation is as above described.

Having thus described our invention and 25 illustrated its use, what we claim is the following:

1. The combination with a highly selective closely tuned wireless telegraph receiving set, of a supplementary broad tuned receiver, and means for tuning the antenna circuit to cause the broadly tuned receiver to respond with maximum effect and arranged to simultaneously vary the tune of the closely tuned receiving set.

2. The combination with a receiving antenna, of a receiver connected thereto and

operating by combined effects of received and locally produced oscillations, a supplementary broadly tuned receiver, and a tuning device adapted to simultaneously tune 40 the antenna and the oscillation producing circuit.

3. The combination with a heterodyne receiver for wireless telegraphy, of a finding receiver, a switch to selectively connect 45 either of said receivers with a receiving antenna, and means to vary the tune of the antenna circuit to cause the finding receiver to respond with maximum effect and arranged to simultaneously tune the heterodyne 50 receiver to the waves being received.

4. In wireless telegraph apparatus, the combination of an antenna, a local generating source of oscillations, a receiver operated by the combined effects of the received and 55 locally generated oscillations, a finding receiver operatively connected to the antenna, and means for simultaneously tuning the antenna and the local oscillation producing circuit.

In testimony whereof, we have hereunto signed our names in the presence of the two 60 subscribed witnesses.

SAMUEL M. KINTNER.
JOHN W. LEE.
